UNITED STATES PATENT OFFICE.

JOHN ROSE, OF PHILADELPHIA, PENNSYLVANIA.

UMBRELLA-RUNNER RETAINER.

SPECIFICATION forming part of Letters Patent No. 427,368, dated May 6, 1890.

Application filed February 3, 1890. Serial No. 339,008. (No model.)

To all whom it may concern:

Be it known that I, JOHN ROSE, a citizen of the United States, and a resident of Philadelphia, Pennsylvania, have invented certain 5 Improvements in Umbrella-Runner Retainers, of which the following is a specification.

One object of my invention is to so construct an umbrella-runner retainer of wire that it can be snugly fitted to and firmly retained in a saw-kerf or opening made in the stick for its reception, a further object being to insure the firm retention of the back bar of the retainer without interfering with the free play of the projecting spring-finger with 15 which the runner engages. These objects I attain in the manner hereinafter set forth, reference being had to the accompanying drawings, in which—

Figure 1 is a vertical section, on an enlarged scale, of part of the stick of an umbrella or parasol with a runner-retainer constructed in accordance with my invention. Fig. 2 is a sectional plan view on the line 1 2, Fig. 1. Fig. 3 is a perspective view of the 25 retainer and a sectional perspective view through the center of the stick, showing the recess for the reception of the retainer; and Fig. 4 is a view of a saw whereby the recess may be formed in the stick.

30 A represents part of the stick of an umbrella or parasol, and B the runner-retainer, which consists of a curved or segmental back bar *a*, with upturned portion *b* at the lower end and a notched or offset portion *d* near the top, the elastic retaining-finger *f* projecting outward at an angle from the top of the back bar and being then bent inward substantially at a right angle to the face of the stick, but terminating in an upwardly-projecting end or hook *g*, the retainer being formed of one piece of wire properly bent, as shown in Figs. 1 and 3.

The retainer is adapted to a segmental saw-kerf or recess *D*, formed in the face of the 45 stick, the back bar of the retainer fitting snugly against the base or bottom of this recess, and the retainer is secured in the recess by means of pins *i* and *m*, which are passed transversely through or partly through the 50 stick, as shown in Fig. 2, the pin *i* engaging

with the notched or offset portion *d* of the back bar of the retainer and the pin *m* engaging with the upwardly bent or hooked end *g* of the projecting spring-finger of the retainer, so as to not only aid in securing the 55 retainer within the recess of the stick, but also to limit the expansion or projection of the spring-finger beyond the face of the stick, as shown in Fig. 1.

The inner portion of the recess *D* in the 60 stick—that is to say, the portion which receives the back bar *a* of the retainer—is of less width than the outer portion of the recess, so that while said back bar of the retainer fits snugly between the walls of the 65 rear portion of the recess the spring *f* will play in the wider outer portion of the recess, as shown in Fig. 2, and hence the free movement of the spring-finger will not be restricted even if the stick shrink or swell. The 70 recess may be readily formed in the stick by the use of a saw such as shown in Fig. 4, this saw having two sets of teeth *x* and *y*, the teeth *x* being longer than the teeth *y* and being without "set," or having but slight set, so as 75 to form the contracted rear portion of the slot or recess in the stick, while the shorter teeth *y* have such an amount of set as will insure the cutting of the outer portion of the slot somewhat wider than the portion formed by 80 the teeth *x*.

Having thus described my invention, I claim and desire to secure by Letters Patent—

1. The within-described runner-retainer for umbrellas or parasols, the same consisting of 85 a single piece of wire bent to form the segmental back bar with notch or offset near one end, upturned finger at the opposite end, and a projecting retaining-finger with hooked or bent end, substantially as described. 90

2. The combination of the retainer having a back bar with notch or offset and an elastic retaining-finger with hooked or bent end, the stick having a recess for the reception of the retainer, and transverse pins engaging with 95 the offset portion of the back bar and with the hooked end of the spring retaining-finger, substantially as specified.

3. The combination of the retainer having a back bar and an elastic retaining-finger 100

with the stick having a recess the rear or inner portion of which receives the back bar of the retainer and is less in width than the outer portion in which the spring-finger works, 5 whereby binding of the latter is prevented, substantially as specified.

In testimony whereof I have signed my

name to this specification in the presence of two subscribing witnesses.

JOHN ROSE.
